UNITED STATES PATENT OFFICE.

GEORGE C. HALE, OF KANSAS CITY, MISSOURI, ASSIGNOR OF ONE-HALF
TO FRED W. GIFFORD, OF KANSAS CITY, MISSOURI.

PLEASURE-RAILWAY.

No. 800,100.

Specification of Letters Patent.

Patented Sept. 19, 1905.

Application filed March 14, 1905. Serial No. 250,464.

To all whom it may concern:

Be it known that I, GEORGE C. HALE, a citizen of the United States, residing at Kansas City, in the county of Jackson and State of Missouri, have invented certain new and useful Improvements in Pleasure-Railways; and I do hereby declare the following to be a full, clear, and exact description of the invention, such as will enable others skilled in the art to 10 which it appertains to make and use the same.

My invention relates to improvements in amusement devices. It has for its object to construct an illusion amusement device in which a person can be made to feel that he is 15 traveling and seeing the sights of some foreign country or State when in reality the vehicle which he occupies is not moving forward at all.

The invention consists, broadly, in constructing and mounting a vehicle in such manner that it may be rocked by the operator to give the impression of going around curves and providing said vehicle with means to give the occupants thereof the feeling of moving rapidly over the rails of a track and railway-crossings, in combination with means to throw a moving picture upon a screen in front of the car.

The invention also contemplates the creation 30 of an artificial air-blast to be directed in the faces of the occupants of the vehicle to add to the deception.

The invention also consists in the details of construction and combinations of parts hereinafter described, and more particularly pointed out in the claims.

In the accompanying drawings, illustrating the preferred embodiment of my invention, Figure 1 is a front elevation of a building in 40 which four of my vehicles are installed, part being broken away and showing two of the tunnels or passages in section on the line $x-x$ of Fig. 2. Fig. 2 is a general floor plan of the building. Fig. 3 is a longitudinal sectional view taken on the line $y-y$ of Fig. 2 through one of the tunnels and showing the positions of the traveling car and the "feeder," as well as the arrangement of the picture-machine and screen. Fig. 4 is an enlarged broken side view of the lower part of the traveling car, showing the way it is mounted. Fig. 5 is a broken vertical cross-sectional view showing the mechanism for rocking the car from side to side. Fig. 6 is a plan view be-

low the car, showing the arrangement of rollers and shafts; and Fig. 7 is a broken longitudinal section view showing the levers for operating the device adapted to engage with the lug-carrying chain to give the impression of going over crossings.

While the preferred embodiment of my invention is illustrated in the accompanying drawings and its construction and operation are described in this specification, the right is reserved to make such changes from the construction shown and described herein as the scope of the claims hereto appended will permit.

In carrying out my invention I construct a housing or building for my device which may 70 be adapted to receive several of the devices, as shown, and is preferably built to resemble on the front the entrance to a railway-depot. Entrance-turnstiles are provided for the admission of the passengers who board a car 75 standing before the entrance of a tunnel. The car may be run by electricity or other suitable motive power and is adapted to run back and forth through the tunnel and convey passengers from the entrance to the other end of 80 the tunnel, where they are transferred to the traveling car. This car in reality does not move forward at all; but I have designated it the "traveling car," because the passengers 85 thereof are made to feel that they are traveling. The movable car or feeder is run back and forth until the traveling car has been filled. The journey then begins. The front of the car is open and the passengers look out directly upon a screen arranged at the end of 90 a dark room or compartment of the building into which the front part of the car projects. Moving pictures taken along a railroad are thrown upon the screen, which is of such size and so arranged as to take up the whole field 95 of vision.

The traveling car is hinged at its longitudinal center upon a stationary framework, under which are arranged rollers resting upon other rollers carried by cross-shafts driven 100 by a suitable motor. Said shafts also carry an endless belt provided with projecting lugs arranged at intervals on its surface. Said lugs come in contact with the upper end of an upstanding flexible metal piece secured to 105 a fixture before the car. The sound of the lugs on the belt striking said metal standard resembles that of the wheels of a car pass-

ing over the joints of the rail of a track, and the interval between the lugs on the belt and the speed of said belt may be varied at will, so that the passengers may be 5 given the impression of moving at any rate of speed desirable. Thus the gradually-increasing speed of a starting train and its diminishing speed as it enters a stopping-place may be realistically reproduced. The revolving 10 wheels below the framework give just enough sound and jar within the car as the wheels of a moving car usually do. Another upright provided with a flanged plate on its upper end is adapted to be raised into 15 engagement with the lug-carrying belt by lever mechanism extending to the rear part of the car, where it may be controlled by the lecturer or "guide." When said flanged plate is raised into contact with the lugs on the 20 belt, it sounds like a train passing over a crossing, and this device is therefore used to great advantage where cossings appear in the picture. The bottom of the car is connected to the supporting-framework also by levers, 25 which are arranged in reach of the operator and by means of which he may tilt the car as a turn appears in the moving picture, thereby giving a very realistic effect. To further add to the completeness of the illusion, a fan or 30 blower is provided and its blast directed in the faces of the occupants of the car. The floor of the car is preferably arranged on an incline to give all the passengers a good view. The exit from the building is preferably 35 separate from the entrance and passes around the side of the tunnel.

Referring more particularly to the drawings, 1 designates the porch of the building; 2, the entrance-lobby, which is reached by 40 the turnstile 3. Said entrance-lobbies are preferably arranged, as shown, between the outer ends of each pair of tracks 4, which pass through the tunnels 5 to the rear platforms 6 of the traveling cars 7. The exit-passages 8 are arranged at the sides of the tunnels, the passengers passing directly from the rear platform 6 of the car 7 through said 45 passage and through a turnstile 8^a, if desired, to the porch 1. A common exit-passage 50 may be provided between the two middle tunnels, and the spaces between the outer and inner tunnels are occupied by the attendants' rooms 9, from which lead the stairs 10 to the lantern-gallery 11, arranged above the level 55 of the cars 7 and slightly rearward thereof in order to get the requisite distance to project the pictures upon the screens 12 and at the same time have said screens close enough to the front of the cars so that they will cover 60 the entire field of vision of the occupants thereof. Each screen is arranged at the end of one of the dark rooms 13, into which the frontends of the cars 7 project. The "feeder-cars," which run through the tunnels 5, are 65 designated 14. While I have provided the

lantern-gallery in front of the screens and mount the picture-machine 15 therein, said picture-machine may be mounted behind the screen and throw the pictures through the screen, if desired, without departing from the 70 spirit or sacrificing the advantages of my invention.

The car 7 is mounted upon the stationary platform 16, to which it is attached by the hinges 17 and upon which it may be turned 75 toward one side or the other by means of the hand-lever 18, extending up through the floor 19 of the car, said lever being pivoted to the platform at 20 and carrying another lever 21, fastened to the floor of the car. By throwing the lever to one side or the other the car is tilted in the same direction. The wheels below 80 the platform are designated 22, and 23 represents the wheels arranged between them and mounted on the cross-shafts 24, carrying the 85 intermediate pulleys 25, upon which runs the endless belt 26, having the projecting lugs 27. The driving engine or motor 28 is connected to the first cross-shaft by belt 29, running over the pulley 30 on said shaft, and the other 90 shafts are driven by the lug-carrying belt 26. The upstanding piece 31, adapted to engage 95 the lugs on the belt 26 to give the sound of passing over rail-joints, is preferably arranged between the two rear shafts, while the other 100 upstanding rod 32, carrying the flanged plate 33, is arranged between the two front shafts and is connected by the rod 34, pivoted at 35, to the hand-lever 36, extending up through the car-floor in reach of the operator. The 105 fan or blower 37 is preferably arranged below the front platform 38 of the car, and its blast passes through the upwardly-extending passage 39 and is directed in the faces of the 110 passengers in the car.

It has been found by actual operation of this amusement device that the illusion is extremely realistic, some of the passengers having been known to clutch the arms of their seats in fright at the apparent great speed of the car and the way it swung over to the side as it took the curves.

Having thus described my invention, what I claim as new, and desire to secure by Letters Patent, is—

1. The combination with a vehicle mounted on a stationary platform, said vehicle having its sides and rear end closed, and means to cause said platform to vibrate to give the impression of movement, of a screen extending across the field of vision from the vehicle and a picture-machine adapted to throw a moving picture on said screen.

2. The combination with a vehicle mounted on a stationary platform and means to create a sound like the wheels of a car going over the rail-joints of a track, of a screen extending across the field of vision from the vehicle and a picture-machine adapted to throw a moving picture on said screen.

3. The combination with a vehicle mounted on a stationary platform and means to create a sound like the wheels of a car passing over the railroad-crossings, of a screen extending across the field of vision from the vehicle and a picture-machine adapted to throw a moving picture on said screen.

4. The combination with a vehicle mounted on a stationary platform and means to blow a blast of air into the faces of the occupants for the purpose specified, of a screen extending across the field of vision from the vehicle and a picture-machine adapted to throw a moving picture on said screen.

15 5. The combination with a vehicle located in the dark, created by natural or artificial means, and mounted on a stationary platform, said vehicle having its sides and rear end closed, and means to cause said platform to vibrate to give the impression of movement, of a screen extending across the field of vision from the vehicle and a picture-machine adapted to throw a moving picture on said screen.

25 6. The combination with a vehicle located in a dark room, said vehicle having its sides and rear end closed and mounted on a stationary platform, of a screen extending across the field of vision from the vehicle and a picture-machine adapted to throw a moving picture on said screen.

30 7. The combination with a vehicle located in a dark room and mounted on a stationary platform, said vehicle having its sides and rear end closed, wheels arranged on said platform and means to revolve said wheels whereby the platform is caused to vibrate to give the impression of movement, of a screen extending across the field of vision from the vehicle and a picture-machine adapted to throw a moving picture on said screen.

40 8. The combination with a vehicle located in a dark room and mounted on a stationary platform, said vehicle having its sides and rear end closed, wheels arranged on said platform, other wheels arranged between the wheel's on said platform and adapted to engage said latter wheels and cause them to revolve for the purpose specified, and means to revolve said second-mentioned wheels, of a screen extending across the field of vision from the vehicle and a picture-machine adapted to throw a moving picture on said screen.

45 9. The combination with a vehicle located in a dark room and mounted on a stationary platform, wheels arranged on said platform, other wheels mounted on cross-shafts and adapted to engage the first-mentioned wheels and cause them to revolve for the purpose specified, means to revolve said shafts and means carried by said shafts for creating a sound like the wheels of a car going over the rail-joints of a track, of a screen extending across the field of vision from the vehicle and a picture-machine adapted to throw a moving picture on said screen.

10. The combination with a vehicle located in a dark room and mounted on a stationary platform, wheels arranged on said platform, other wheels mounted on cross-shafts and adapted to engage the first-mentioned wheels and cause them to revolve for the purpose specified, means to revolve said shafts, a belt carrying lugs, mounted in said shaft, and a piece extending within the path of said lugs for the purpose specified, of a screen extending across the field of vision from the vehicle and a picture-machine adapted to throw a moving picture on said screen.

15 11. The combination with a vehicle located in a dark room and mounted on a stationary platform, wheels arranged on said platform, other wheels mounted on cross-shafts and adapted to engage the first-mentioned wheels and cause them to revolve for the purpose specified, means to revolve said shafts, a belt carrying-lugs, mounted on said shaft, and a plate adapted to be brought into the path of said lugs for the purpose specified.

20 12. The combination with a vehicle located in a dark room and mounted on a stationary platform, wheels arranged on said platform, other wheels mounted on cross-shafts and adapted to engage the first-mentioned wheels and cause them to revolve for the purpose specified, means to revolve said shafts, a belt, carrying-lugs, mounted in said shaft, a plate adapted to be brought into the path of said lugs for the purpose specified, and means for operating said plate extending in reach of the operator, of a screen extending across the field of vision from the vehicle and a picture-machine adapted to throw a moving picture on said screen.

25 13. The combination with a vehicle located in a dark room and mounted on a stationary platform, and means to rock said vehicle on said platform, of a screen extending across the field of vision from the vehicle and a picture-machine adapted to throw a moving picture on said screen.

30 14. The combination with a vehicle located in a dark room and mounted on a stationary platform, and means to rock said vehicle on said platform extending within reach of the operator, of a screen extending across the field of vision from the vehicle and a picture-machine adapted to throw a moving picture on said screen.

35 15. The combination with a vehicle located in a dark room and hinged near its longitudinal center to a stationary platform, and means to turn the vehicle on the hinge, of a screen extending across the field of vision and a picture-machine adapted to throw a moving picture on said screen.

40 16. The combination with a vehicle located in a dark room and connected to a stationary platform by means of a central hinge, said vehicle adapted to tilt sidewise on said platform, and a series of levers terminating within

the vehicle, for tilting said vehicle, of a screen extending across the field of vision from the vehicle and a picture-machine adapted to throw a moving picture on said screen.

- 5 17. The combination with a vehicle located in a dark room and mounted upon a stationary platform, said vehicle having its sides and rear end closed, of means to cause said platform to vibrate for the purpose specified, a screen extending across the field of vision and a picture-machine adapted to throw a moving picture on said screen, and another vehicle adapted to bring passengers from without to said first-mentioned vehicle.
- 15 18. The combination with a vehicle located in a dark room and mounted upon a stationary platform, of means to cause said platform to vibrate for the purpose specified, a screen extending across the field of vision and a picture-machine adapted to throw a moving picture on said screen, a dark passage extending from without to said dark room, and another car adapted to run in said passage and bring the passengers to said first-mentioned vehicle.
- 25 19. The combination with a vehicle mounted on a stationary platform and located with its front portion extending into a dark room and the rear extending into a dark passage, another vehicle adapted to run through said passage to bring passengers to the first-mentioned vehicle, an exit-passage from the rear end of said first-mentioned vehicle without said passage, a screen extending across the field of vision and a picture-machine adapted
- 35 to throw a moving picture on said screen.
20. The combination with a vehicle mounted on a stationary platform and located with its front portion extending into a dark room and

the rear portion extending into a dark passage, another vehicle adapted to run through said passage to bring passengers to the first-mentioned vehicle, an exit-passage, a screen extending across the field of vision for the vehicle in the dark room, and a picture-machine, arranged in a gallery above the passage, adapted to throw a moving picture on said screen.

21. The combination with a vehicle open at one end and located in a dark place on a suitable frame, and means to cause said vehicle to vibrate and oscillate to give the effect to the occupants of said vehicle of riding toward the opening, of a screen arranged in front of the open end of the vehicle and covering the entire view through said open end, and a picture-machine arranged to throw a moving picture upon said screen.

22. The combination with a vehicle open at one end and located in a dark place, a supporting-frame for said vehicle, upper and lower sets of wheels on said frame, other wheels mounted on cross-shafts and arranged between, and adapted to engage, said first-mentioned wheels and cause them to revolve, for the purpose specified, and means to revolve said shafts, of a screen arranged in front of the open end of the vehicle and covering the entire view through said open end, and a picture-machine arranged to throw a moving picture upon said screen.

In testimony whereof I affix my signature in presence of two witnesses.

GEORGE C. HALE.
